APPARATUS FOR SURFACE TREATMENT OF
GREEN CLAY

Edwin Barker Jones, Wallasey, England

Application July 6, 1937, Serial No. 152,235
In Great Britain October 28, 1936

3 Claims.

(Cl. 25—1)

The present invention relates to the treatment of plastic materials, and is particularly applicable to the treatment before burning of green clay, shale or the like products such as bricks or tiles.

5 The chief object of the invention is to provide improved means for producing so-called facing bricks.

A further object of the invention is to provide an improved means for producing facing bricks

10 which will operate satisfactorily over a wide range of speed of the clay column. Certain known forms of apparatus for treating columns of clay will only operate satisfactorily up to certain fairly well defined clay column speeds and at higher speeds they operate somewhat unsatisfactorily and it is an object of the invention to avoid this disadvantage.

15 A further object of the invention is to provide an apparatus for the surface treatment before burning of green clay, shale or like products such as bricks, comprising means for moving the product along a predetermined path, a rotatable carrier spaced from said path with its axis of rotation inclined at an angle to the path of travel of the product, a number of beaters or flails mounted on and movable relatively to said carrier and means for rotatably driving the carrier to cause the beaters or flails to extend outwards from the carrier under the action of centrifugal force, whereby to beat the product during its treatment.

20 The flails or beaters may consist of chains or alternatively they may consist of flexible arms or wires which may have small balls at their free ends adapted for engagement with the clay product. Again, instead of providing relatively small balls on the ends of the beater arms, the balls may, if desired, be eliminated and the ends of the arms bent over and the beating carried out by such ends of the arms, particularly where the beater arms are of flat section material.

25 The flails may be movable relatively to the carrier either by virtue of their mode of connection to the carrier or of their inherent flexibility or both.

30 Sand, powder, or other suitable comminuted facing material may be applied to the surface or surfaces of the products preferably before the beating action takes place but if desired it may be applied simultaneously with or subsequent to the beating action.

35 The invention is more particularly described with reference to the accompanying somewhat diagrammatic drawings in which:—

40 Figure 1 is a side elevation,

45 Figure 2 an end elevation and

50 Figures 3 and 4 are a side and end view respectively of a beater assembly.

55 Referring first of all to Figures 3 and 4, the carrier consists of a roller 10 having circum-

ferentially spaced axial dove-tail grooves 11 which receive bars 12 of dove-tail section. Each bar 12 has a series of apertured lugs 13 through which a wire 14 is threaded. The chains 15 are mounted on the wires 14 and are spaced apart by the lugs 13. If desired, of course, a number of chains may be provided in the space between each two lugs and such chains may be spaced apart by suitable distance pieces or washers.

60 A clay column is indicated by the numeral 16 and is movable in the direction indicated by the arrow 17. The roller 10 is disposed above the clay column and is mounted on shaft 20 driven by pulley 21. Pulley 22 is a loose pulley. As will be observed, the roller 10 bearing the chains 15 is arranged with its axis of rotation at right angles to the direction of movement of the clay column.

65 An auxiliary shaft 23 is driven from shaft 20 through chain wheels and chain 24. Shaft 23 has a side-faced cam 25 thereon, which engages with a roller 26 at one end of a lever 27 pivoted on a spindle 28. The other end of lever 27 has a fork 29 which engages the end 30 of roller 10. Thus by means of the cam 25 and lever 27 the roller 10 is periodically axially displaced 70 against the pressure of a spring 31 whereby to ensure irregularity of and to avoid readily perceptible repetition in the resultant configuration of the surface of the product.

75 For treating the side surfaces of the clay column vertical rollers 36 are arranged at each side of the path of travel of the column, such rollers having chains mounted thereon as described in connection with roller 10. The rollers 36 are driven through bevel gear pairs 37, 38 and chain 39 from the shaft 20. As in the case of the roller 10, each roller 36 is adapted for axial displacement during its rotation. The axial displacement is effected, against the resistance of a spring 40, by means of rollers 41 mounted at the end of levers 42 fixedly connected to a rock-shaft 43 on which is secured an upwardly extending lever 44, provided at its end with a roller 45 adapted for engagement with a cam 46 mounted on the shaft 23. Thus the roller 36 and the chains attached thereto are periodically vertically displaced so as to vary the point of engagement of the respective chains with the clay.

80 Sand, powder or like facing material is supplied to the respective surfaces of the column from a hopper 50 and pipes 51, 52, 53. For the sake of clearness the ends only of pipes 52, 53 are indicated in Figure 2 and their connections to the hopper are not shown. The flow of sand from the hopper into the pipe 51 is controlled by a slide 54 and a similar slide is provided for each of the pipes 52, 53. Excess sand supplied to the clay column falls on a sieve tray 55 from which 85

it passes into a receiving trough 56. The sieve tray 55 is mounted on swing links 57 and is given a jiggling motion by means of a lever 58 which is mounted on the oscillating shaft 43 and which at its free end is connected through a link 59 to a projection extending upwardly from the tray. From the space 56 the excess sand is conveyed by a worm conveyor 60 to an outer receiver 61 from whence it is raised by a bucket conveyor belt 10 62 and returned to the hopper 50.

The bucket conveyor 62 is driven by a pulley 63 mounted on the shaft 64 driven through a bevel gear pair 65 and chain 66 from the shaft 23. The conveyor 62 drives a pulley 67 at its lower end which through a bevel gear pair 68 drives the worm conveyor 60.

The speed of rotation of the carrier has an important bearing upon the nature of the treatment and upon the finished appearance of the bricks. It has been found that using a roller of 3 3/4" diameter as the carrier with its axis spaced 5 1/4" from the clay column and with chains about 4" long, a satisfactory appearance was obtained when the carrier was rotated at 560 revs. per 25 minute, and the clay column moved at 8-10 ft. per minute. In this case the links of the chain were 5 1/8" long and the links were formed of 1/16" diameter wire.

I declare that what I claim is:—

1. Apparatus for the surface treatment before burning of green clay, shale or like products such as bricks, comprising means for moving the product along a predetermined path, a rotatable carrier spaced from said path with its axis of rotation inclined at an angle to the path of travel of the product, a number of beaters or flails mounted

on and movable relatively to said carrier and means for rotatably driving the carrier to cause the beaters or flails to extend outwards from the carrier under the action of centrifugal force and thus to beat the product during its movement. 5

2. Apparatus for the surface treatment before burning of green clay, shale or like products such as bricks, comprising means for moving the product along a predetermined path, a rotatable carrier spaced from said path with its axis of rotation inclined at an angle to the path of travel of the product, a number of beaters or flails mounted on and movable relatively to said carrier, means for rotatably driving the carrier to cause the beaters or flails to extend outwards from the carrier under the action of centrifugal force and thus to beat the product during its movement, and means for axially displacing the carrier during its rotation to ensure irregularity 10 15 of and to avoid readily perceptible repetition in the resultant configuration of the surface of the product.

3. Apparatus for the surface treatment before burning of green clay, shale or like products such as bricks, comprising means for moving the product along a predetermined path, a rotatable carrier spaced from said path with its axis of rotation inclined at an angle to the path of travel of the product, a number of lengths of chain 25 30 35 mounted on said carrier, and means for rotatably driving the carrier to cause the chains to extend outwards from the carrier under the action of centrifugal force and thus to beat the product during its movement. 35

EDWIN BARKER JONES.
